UNITED STATES PATENT OFFICE

WARREN B. HARRIS, OF MILLBURY, MASSACHUSETTS.

SHUTTLE-CHECK FOR LOOMS.

No. 841,863.

Specification of Letters Patent.

Patented Jan. 22, 1907.

Application filed October 18, 1906. Serial No. 339,436.

To all whom it may concern:

Be it known that I, WARREN B. HARRIS, a citizen of the United States, residing at Millbury, in the county of Worcester and State of Massachusetts, have invented a new and useful Improved Shuttle-Check for Looms, of which the following is a specification, reference being made therein to the accompanying drawings.

This invention relates to an improved means for receiving the impact and checking the movement of shuttles and pickers in looms, the object of my invention being to provide in a shuttle-check a novel construction and combination whereby a proportion of the impact force is exhausted or borne by an inclined solidly-stationary abutment member at or upon the end of the lathe or shuttle-box and coacting with a yieldable member and a peculiarly-disposed resistance-spring, thereby relieving the spring and mechanism from shocks and strains that might otherwise tend to break, set, or injure the spring. These objects I attain by the mechanism illustrated in the accompanying drawings, wherein—

Figure 1 represents a rear elevation view of my improved shuttle-check together with such parts of a loom as will show the manner 30 of its combination therewith. Fig. 2 represents a plan view of the same; and Fig. 3 represents a sectional view of the check device, showing certain modifications.

Referring to the parts on the drawings, the letter A denotes the shuttle-box head-frame or guide-casting at the end of the lathe or batten of a loom, and a indicates the evener or guard-flange employed with drop-boxes for keeping the shuttles even and made integrally with the guide-casting, but omitted in single-box looms. B indicates the shuttle box or boxes supported on or guided by the head-casting. C indicates the picker-guiding rod, D the picker sliding on said rod for throwing the shuttle F from the shuttle-box. Said parts represent the usually-employed elements and may be of a loom made for operating in well-known or any suitable manner, and being, together with the means for the operation thereof, well understood further illustration and description thereof herein is not necessary except in their special relation to the means which embodies my invention.

In accordance with my invention I provide a check-body member 2, which consists of a

block or abutment secured in stationary position upon the part of the lathe by screws or otherwise adjacently beyond the end of the shuttle-box and having an inclined bearing-surface 5 disposed oblique to the axis of the shuttle-box or direction in which the shuttle moves. Combined therewith I arrange a movable block or contact member 3, having an inclined seating-surface countermatching 60 with and slidably supported upon the inclined surface 5 of the body member 2. The slide block or member 3 is also provided with a contact-face 6, approximately perpendicular to the line of the shuttle movement and 65 disposed at a position in line with the shuttle-point and adapted to receive the impact contact of the moving shuttle and picker-head when the latter is forced back by the incoming shuttle entering the shuttle-box in the direction indicated by the arrows. 70

A spring-holding means, as bolt 7, is arranged through a hole in the body-block 2 and through a longitudinal slot 8 in the slide-block 3. Said bolt is disposed approximately perpendicular to the line of shuttle movement and is provided with a head 9 at one end and with an adjusting nut or nuts 10 at its other end. Seating-washers 12 and 13 are preferably arranged loose upon the bolt 80 7, adjacent to the top of the contact-block 2 and against the nut 10. An expanding coiled-wire spring 15 is arranged about the bolt in such manner that the tension of the spring tends to force the contact block or 85 member 3 down the inclined surface 5 on the body member 2 and toward its forward or primal position, as shown in Fig. 1. The bolt 7 may be disposed with the spring above the contact-block, as shown in Fig. 1, or beneath the body-block, as shown in Fig. 3, as the action and effect are substantially the same in either form. The tension of the spring can be regulated by means of the nut 10. The contact-face of the slide-block can 90 be made with a cushion-facing 16, of leather or other non-metallic material, as indicated in Fig. 3, or the contact-face can be formed directly upon the metal of the block, as preferred. The inclined surface 5 may be varied in its degree of obliqueness in different instances to afford greater or less resistance to the movement of the contact member 3. 95

In the operation when the shuttle comes into the shuttle-box, forcing back the picker, the impact thereof is received on the face 6 of the slide-block or contact member 3, which 100

moves up the incline 5, compressing the spring 15, and the momentum of the shuttle is yieldingly checked by the resistance offered by the stationary abutment member and the 5 retreatable contact-block seated against the inclined surface 5 and moving thereon opposed by the transversely-applied pressure of the spring 15. A considerable proportion of the impact force is exhausted against the 10 fixed body-block 2 without rigidity, and the spring 15 is not subjected to severe shocks that would tend to set, fracture, or quickly destroy the spring. Furthermore, the combination is such that a spring of ample length 15 in proportion to its extent of compression can be conveniently employed without interfering with other parts of the mechanism, thus affording a check device that is very efficient, durable, and smoothly operative.

20 I claim and desire to secure by Letters Patent—

1. A shuttle-check mechanism, comprising a stationary member having a bearing-surface the plane of which is oblique in relation 25 to the line of the shuttle movement, a contact-receiving member having an inclined seating-face supported and slidable upon said bearing-surface, a spring-holding means, and a spring pressing said contact member 30 toward said inclined bearing-surface in a direction approximately perpendicular to the line of shuttle movement.

2. A shuttle-check for looms, comprising a stationary body block or member having an inclined bearing-surface, a longitudinally-slotted slide-block having a contact-face and an inclined seating-face slidably supported upon the inclined bearing-surface of said body member, a projecting spring-guiding bolt arranged transversely through said 40 blocks, and a spring disposed for pressing upon said slide-block in a direction oblique to the plane of said bearing-surface.

3. The combination with the lathe, shuttle-box, and picker, in a loom; of a check-body fixed on the lathe and having an inclined bearing-surface oblique to the axis of the shuttle-box, a movable contact member having a perpendicular contact-face and an inclined seating-face supported upon the 45 bearing-surface of said check-body, a bolt passing through said body and contact member approximately perpendicular to the line of shuttle-box axis, a coil-spring arranged on said bolt and exerting pressure to impel said contact member toward its primal position, and means for regulating the tension of said 50 spring.

Witness my hand this 15th day of October, 1906.

WARREN B. HARRIS.
